J. H. McLean
 Design for a Trade Mark
 Patented Oct. 11, 1859.

James H. Mc Dean, of St. Louis, Mo.
Letters Patent No. 1155. Dated Oct. 11. 1859.

Des. 1155

The schedule referred to in these Letters Patent and making part of the same.

To all whom it may concern:

Be it known that I, James H. Mc Dean, of the City and County of St. Louis and State of Missouri, have produced a new and original design, for a print or picture to be printed upon paper and used on an article of manufacture known as "J. H. Mc Dean's Strengthening Cordial and Blood Purifier".

And I do hereby declare that the following is a full, clear and exact description of the said design, reference being had to the annexed drawing making part of this Specification, in which there are seven persons represented, and a box of bottles containing the cordial aforesaid.

This bottle is marked A, and the figure marked B represents the maker and inventor of the said Cordial, and to the right of this last mentioned figure, there are three more figures seen which represent so many persons in apparent delicate health, marked D, E, F, the figure F, being represented in the act of receiving a bottle of the said Cordial from the said inventor and maker, and to the left of the figure B, there are three more figures, seen marked C, P, Q, in apparent robust health, the figure C, representing a child swinging his hat in a spirit of joyfulness, and with his hand joined to that of the woman P, who is leaning upon the arm of the man Q, who has a cane in his left hand.

The figure D, also represents a child with a cane in his right hand, and with his left hand joined to that of the woman E, who is leaning upon the arm of the man F.

The above described drawing is enclosed in a suitable border, and may be otherwise embellished. But what I claim as my invention or jurisdiction, and desire to secure by Letters Patent is the design shown by the annexed drawing, and described herein, to be used as a Trade mark upon an article of manufacture with the name thereon inscribed.
